UNITED STATES PATENT OFFICE.

WALTER D. CRAFT, OF NEWARK, NEW JERSEY, AND FRANK F. SORENSEN, OF PHILADELPHIA, PENNSYLVANIA.

MILLING-MACHINE.

1,356,807.

Specification of Letters Patent. Patented Oct. 26, 1920.

Application filed August 18, 1919. Serial No. 318,125.

To all whom it may concern:

Be it known that we, WALTER D. CRAFT and FRANK F. SORENSEN, citizens of the United States, and residents, respectively, 5 of Newark, in the county of Essex and State of New Jersey, and of Philadelphia, in the county of Philadelphia and State of Pennsylvania, have jointly invented a certain new and useful Milling-Machine, of which the 10 following is a specification.

The principal objects of the present invention are, first, to present the cutting operation to the convenient view of the operator; second, to facilitate the removal of 15 chips; third, to provide for continuous milling; fourth, to provide for the convenient setting or adjustment of the machine; fifth, to make the machine automatic and accurate in operation, and sixth, to provide a 20 compact, efficient and reliable milling machine well adapted to the rapid production of cut or milled files.

The invention will be claimed at the end hereof, but will be first described in connection with the embodiment of it selected 25 for illustration in the accompanying drawing, forming part hereof, and in which—

Figure 1, is an end view, principally in transverse section, of a milling machine embodying features of the invention.

Fig. 2, is a rear view of the machine.

Fig. 3, is a front view, partly in section.

Fig. 4, is a top or plan view of the carriage and its accessories detached, and

Fig. 5, is a horizontal sectional view of a portion of the carriage.

In the drawings 1, is a laterally sloping horizontally extending bed. 2, is an inclined carriage provided with a work-holder 3 and 40 longitudinally slidable on the sloping bed 1, being driven by a screw 4. 5, is a fixed head overhanging the sloping bed 1. 6, is a tool shaft substantially perpendicular to the sloping bed 1. 7, is a slide carried by 45 the head, as shown in Fig. 3 by pin-and-slot connections 8. The bearing 7^a of the tool shaft 6, is adjustable endwise on the slide by means of the hand-wheel 9, gearing 10 and screw 11, and the purpose of this is to 50 afford a fine adjustment of the tool. The shaft 6 is driven from the shaft 12, by gearing 13 and it is tubular for the purpose of lubricant, which may be introduced at 14. 15, is a lever pivoted at 16 and one end of 55 it works in a fork in the slide 7 and the

other end is controlled by the pin working in a cam 17, pivoted at 18. This mechanism serves to lift the tool shaft 6 into and out of action. 19, is an endwise movable rack shaft which meshes with teeth on the cam 60 17 and which serves, when in extreme right-hand position as shown in Fig. 1, to lift the slide 7 and tool shaft 6 and which serves, when in extreme left-hand position, to turn the cam 17 into position for locking the 65 slide 7 against the adjustable stop 20, so that when the machine is running the tool shaft is locked or held against upward endwise motion. The rack shaft 19, is operated by suitable provisions 21 on the carriage 2, and 70 also when desired by means of a handle 22, Fig. 2, that operates through the link 23 and shaft 24. The power shaft 25 is driven from the shaft 12 by gearing 26 and this power shaft 25 can be connected to drive the 75 feed screw 4 by power and disconnected to permit the feed screw to be turned by hand, as will be described.

There is a worm-shaft 27 having a worm 27^a, Fig. 5, and which may be driven by 80 means of a handle 28 (Fig. 1) and which can be coupled with and uncoupled from the power shaft 25 by means of a coupling 29 (Fig. 5) operated by a hand-shift 30. The worm-shaft 27 drives the clutch member 31 85 at relatively slow speed through the worm gear 32 and the worm-shaft 27 drives the clutch element 33 at relatively high speed and in the reverse direction through gearing 34. The clutch element 35, shiftable 90 through the shaft 36 either by the handle 37 or by the arm 38, can be made to engage with either of the clutch elements 31 or 33 and so the clutch element 35 serves to drive the feed screw drive shaft 39 rapidly in one 95 direction, which is the direction of retraction of the work and slowly in the other direction, which is the direction of cutting. The arm 38 on the shaft 36 is operated by tappet mechanism 40, actuated by the travel 100 of the carriage, Fig. 2, and the spring detent 41 controls the movement of the shaft 36. The rod *a*, is afforded endwise motion in bearings *b*, mounted on the fixed bed and this rod is connected pivotally by element 40, with part 38. *c*, is one of two duplicated collars on the rod *a*, and these collars are tapped by the part 21, Fig. 1, on the carriage. The other collar is concealed in Fig. 2, but will be readily understood. The feed 110

screw drive shaft 39 carries one of the change gear-wheels 42, of which the other 43 (Fig. 1) is mounted on the end of the feed screw 4. The idler gear wheel 44 is mounted on a stud radially adjustable in an arm 45 mounted to swing on shaft 39 and adjustable in circular direction by the curved slot-and-pin connection 46. In this way the gears 42 and 43 can be removed and replaced by others appropriate for producing the speed of the screw 4 required for various kinds of work.

The machine is well adapted to continuously cut spiral teeth on file blanks, of which one A is shown as clamped in the work-holder. For this purpose, use is made of a crown cutter, shown at B, mounted on the shaft 6 but it must be borne in mind that the use of the machine is not limited to the milling of file teeth. However, when a crown cutter is used for this purpose the bearings in the slide and head for the shaft 6 are set at a slight inclination to the perpendicular to the face of the inclined work-holder, as indicated in Fig. 3 by the broken lines X—Y, and in this way clearance is afforded for the cutter. Of course for some kinds of work this inclination is not necessary.

In use a blank is mounted in the work-holder while the tool is retracted, as shown in Fig. 1, and then the tool is brought down to its work and the slide is locked against the stop 20, as has been described, and the carriage is fed forward by the screw 4 at the appropriate speed. Upon the completion of the forward stroke, the tool is retracted into the position shown in Fig. 1, and the carriage returns comparatively rapidly as has been described. In the case of the continuous milling of files, the entire face of the file is milled during the described operation so that the production of files is very rapid. The sloping position of the work and the inclination of the tool shaft, which is substantially perpendicular to the sloping face of the work is important. Among other things it affords the operator a good view of the performance of the work and it enables the lubricant, assisted by gravity, to remove chips and cuttings. The lubricant may be collected in the receptacle 50, from which it can be returned to the inlet 14. While the machine is driven by power, both the tool and the carriage can be moved by hand as has been described, which is a matter of great convenience and since the speed of the feed of the car-

riage can be readily changed by the use of proper speed gears, the machine is of quite universal application. The fact that the tool is locked by a cam as 17 against a stop as 20 up to its work is important because it insures accuracy.

We claim:

1. A milling machine comprising the combination of a laterally sloping horizontally extending bed, an inclined carriage longitudinally slidable on the sloping bed, a fixed head overhanging the sloping bed, a tool shaft perpendicular to the sloping bed and turnably mounted in the head, whereby the operation is visible and chips are removable, and means for reciprocating the carriage and turning the shaft, substantially as described.

2. A milling machine having in combination a sloping reciprocating work-holder, an inclined revoluble tool shaft perpendicular to the sloping face of the work-holder, feed and return mechanism for the work-holder, devices for advancing and retracting the shaft in response to the travel of the holder, and cam and stop means responsive to said devices for locking the shaft in advanced position during the forward stroke of the holder.

3. A milling machine comprising the combination of a laterally sloping horizontally extending bed, an inclined carriage longitudinally slidable on the sloping bed, a fixed head overhanging the sloping bed and having a bearing of which the axis is slightly inclined lengthwise of the bed to afford tool clearance, a tool shaft substantially perpendicular to the sloping bed and turnably mounted in the bearings, and means for reciprocating the carriage and turning the shaft.

4. A milling machine comprising the combination of a laterally sloping horizontally extending bed, an inclined carriage longitudinally slidable on the sloping bed, a fixed head overhanging the sloping bed, a slide carried by the head and movable substantially perpendicular to the sloping bed, a stop for the slide, a turnable shaft adjustably carried by the slide and inclined in respect to the sloping bed, slide shifting mechanism responsive to the movement of the carriage and including a cam surface adapted to lock the slide in respect to its stop, and means for operating the carriage and shaft.
